UNITED STATES PATENT OFFICE

BRUNO FASSMANN, OF TEMPELHOF, BERLIN, GERMANY, ASSIGNOR TO ADDRESSOGRAPH COMPANY, OF CHICAGO, ILLINOIS, A CORPORATION OF DELAWARE

SELECTION APPARATUS OF ADDRESSING AND OTHER SIMILAR PRINTING MACHINES

Application filed December 17, 1929, Serial No. 414,789, and in Germany October 14, 1926.

This invention relates to selection apparatus of addressing and other similar printing machines, of the kind in which printing plates fed into the machine control, by the 5 action of indicators such as riders, tabs, projections, depressions, or recesses located in or on the printing plates or their holders, certain processes of the machine, such as the application or withdrawal of the printing 10 pressure. Groups of switches adjusted on a selector in such apparatus have had only an individual effect or action, that is to say, all the printing plates having indicators which corresponded with individual switches of the 15 group were used for control purposes. As the indicators of a printing plate do not all necessarily correspond with one adjusted group of switches, the difficulty arises that they cannot be used for a group action, so as to augment or manifold the adjustments and adapt 20 them to different office organizations. An object of the present invention is to overcome this difficulty.

The salient objects of this invention are to 25 provide a selection apparatus comprising a switching-over device that may be readily positioned for so-called group action or for individual action; to provide a switching device comprising stationary and movable contacts that may be actuated by indicators on 30 the printing devices; to provide a selector wherein the electrical connections will be so arranged that passage of the current therethrough may be regulated in order that only 35 desired circuits may be closed; and to provide a selector having relays therein so arranged in the circuits that fluttering thereof will be prevented.

In the accompanying drawing the invention 40 is schematically illustrated and the electrical connections are diagrammatically shown.

In order that the invention may be clearly 45 understood and readily carried into effect, the same will now be described more fully with reference to the accompanying drawing wherein a plurality of stationary contacts o^1 to o^5 are shown as being carried by a block or blocks of insulating material 1, and arranged on 50 these blocks in spaced relation with the sta-

tionary contacts o^1 to o^5 are movable contacts k^1 to k^5 , and arranged above the blocks 1 and the contacts k^1 to k^5 is a block or blocks of insulating material 2, and carried by these blocks of insulating material 2 and disposed above the contacts k^1 to k^5 are contacts b^1 to b^5 , and normally the movable contacts k^1 to k^5 are in engagement with the stationary contacts b^1 to b^5 . The printing devices indicated by a are movable through guideways 3 by a suitable feeding device generally indicated by 4 which may be of a character described in the Duncan patent No. 1,481,860, patented January 29, 1924, and this feeding device sequentially moves the printing devices 60 a through the guideways 3 first into the selecting position wherein the printing device a is shown and then into printing position wherein the printing device a' is shown. Impressions are made from the printing device a' through the suitable ink ribbon R by a platen 5 carried by the platen arm 6 including a bearing 7 pivotally mounted on the frame 8 of the machine. The machine also includes a driving pulley 9 mounted on a shaft 75 10 and receiving power through a belt 11 from a suitable source of power such as an electric motor. On the shaft 10 is a crank arm 12 having a link 13 connected thereto which is pivotally connected at 14 to a rocker 15 pivotally mounted on the frame 8 at 16. Pivotally mounted on the rocker 15 at 17 is a link 18 having a notch 19 therein, and a pin 20 on a portion of the platen arm 6 depending below the bearing 7 thereof is disposed in the 80 notch 19 to thereby connect the platen arm 6 to the link 18 and the rocker 15 so that as the driving pulley 9 is operated a reciprocating movement will be imparted to the platen 5 to thereby apply a printing pressure. As 90 is well understood in the art, the operation of the feeding device 4 and the platen 5 are in timed relation relative to each other and the printing device is first moved through the selecting position before moving into printing position, and when in selecting position the selection apparatus determines whether or not the platen 5 is to be operated, and this is brought about in the following manner:

The indicators previously referred to are 100

in the present instance tabs 22 and the device is, in the disclosed embodiment, arranged for group action, that is, tabs, such as 22, must be in the three positions indicated before the platen will be rendered operative. Detecting fingers 23 are pivotally mounted on a shaft 25 and are disposed to be engaged by the tabs 22 on the printing device *a* in selecting position, and each of these detecting fingers 23 includes a block of insulating material 24 which respectively rests on the movable contacts k^1 to k^5 and in the present instance I have shown but five of such detecting fingers and cooperating sets of contacts, but it is to be understood that a greater or less number might be provided in accordance with the construction of the machine with which the device is used. In order to determine the group action a plurality of switches e^1 to e^5 are provided, and these switches are of the character which may be moved downwardly into circuit closing position and retained therein, the plungers thereof including shoulders which engage a suitable latching device. When the plungers of the switches e^1 to e^5 are moved downwardly they close a circuit between the cooperating pairs of contacts that are respectively indicated by x^1 to x^5 and y^1 to y^5 . Conductors t^1 to t^5 respectively interconnect the contacts k^1 to k^5 and x^1 to x^5 . The contacts y^1 to y^5 are each connected to a conductor 26 which is connected to one terminal of the winding of a controlling relay *g*, a conductor 27 being connected to the other terminal of this winding and to a conductor 29 which is connected to one terminal of a source of current *i*. A conductor 28 is connected to the other terminal of this source of current. The conductor 29 is also connected to one terminal of the winding of the operating relay *h*, the other end of this winding being connected through a conductor 30 to the armature *m* of the relay *g*, which armature is movable between contacts *p* and *n* and which is normally urged into engagement with the contact *p* by the spring 31. The contact *p* is connected through a conductor 32 to the terminal 33 of the switching-over device *f*. The contact *n* is connected by a conductor 35 to the contact 36 of the switching-over device *f*. The conductor 28 is connected to the switch blade 37 of the switching-over device *f*. The contact 36 of the switching-over device *f* is connected through a conductor *s* to each of the contacts o^1 to o^5 while the contact 33 of the switching-over device is connected through the conductor *r* to each of the contacts b^1 to b^5 . When the device is to be arranged for group action, the switch blade 37 is engaged with the contact 33. A circuit is therefore established from the source of current *i* through the conductor 28, switch blade 37, contact 33, conductor *r*,

to the various contacts b^1 to b^5 , through the various contacts k^1 to k^5 , and the conductors t^1 to t^5 to the contacts x^1 to x^5 . The nature of the group action will be determined by selectively closing certain of the switches e^1 to e^5 and in the present instance the switches e^2 , e^3 , and e^5 are closed, and manifestly this arrangement corresponds to the positions of the tabs 22 on the printing device *a* in selecting position. Therefore, the circuit will be established through the plungers of the switches from the contacts x^2 , x^3 and x^5 to the contacts y^2 , y^3 and y^5 and thence through the conductor 26 to one end of the winding of the relay *g* and through the conductor 27 to the conductor 29 and thence to the other terminal of the source of current *i*. This energizes the controlling relay *g* and the armature *m* is attracted thereby and contacts with the contact *n* which is connected to the contact 36 on the switching-over device *f* and which is therefore isolated from the circuit. However, when a printing device having tabs positioned as the tabs 22, which correspond to the closed ones of the switches e^1 to e^5 , moves into printing position the detecting fingers 23 are moved, and in this instance the contacts k^2 , k^3 and k^5 will be disengaged from the contacts b^2 , b^3 and b^5 and therefore the circuit to the winding of the relay *g* will be broken, the circuit between the contacts b^1 and k^1 and b^4 and k^4 being opened by reason of the disposition of the switches e^1 and e^4 . The de-energizing of the controlling relay *g* permits the spring 31 to move the armature *m* into engagement with the contact *p* and therefore an electric circuit will be closed as follows: The current will flow from one terminal of the source *i* through the conductor 28, switch blade 37 to contact 33, through conductor 32, contact *p*, armature *m*, conductor 30, winding of the relay *h*, through the conductor 29 to the other terminal of the source *i*, and therefore the operating relay *h* will be energized to thus attract the armature 40 which is pivotally mounted at 41 on the frame 8 and therefore the nose 42 on this armature will be retracted from engagement with the nose 43 on the dog 44 fixed on the shaft 45, which extends below the guideways 3, and on the other end of the shaft 45 is a dog 46 having a roller 47 thereon adapted to be engaged by the block 48 on the link 18. Prior to the time the armature 40 was attracted the nose 42 engaged the nose 43 and therefore positioned the dog 44 and thus the shaft 45, dog 46 and roller 47 so that the block 48 engaged said roller and held the link 18 in the position illustrated whereby the notch 19 was disengaged from the pin 20, and it is therefore manifest that the platen arm 6 was not connected to the rocker 15 and therefore was not operating. But, when the armature 40

is attracted and the noses are disengaged, the spring 49 moves the dog 44 and the parts carried thereby so that the roller 47 disengages the block 48 and therefore the notch 19 may engage the pin 20, and therefore the link 18 will motivate the platen arm 6 to apply printing pressure through the platen 5. The block 48 will move beyond the position of the roller 47 when the platen moves in the performance of a printing operation, and on the return stroke the block will engage the roller and therefore the shaft 45 and dog 44 will be moved and the projection 50 on the dog 44 will engage the latch 51 that is urged into engaging position by the spring 52, and when the parts are so positioned the nose 43 will have again moved below the nose 42 and the latch 51 will hold the parts for a short time during the changing of the printing devices. If a printing device similar to the printing device *a* moves into selecting position, the circuit to the operating relay *h* will again be closed and the armature 40 will again be attracted and therefore the spring 49 will again move the parts, as above described, to bring about interengagement of the pin 20 and the notch 19, the latch 51 serving to hold the parts during the time the circuit is broken which occurs when the printing devices are changing. If, however, the printing device which moves into selecting positions does not have tabs positioned as illustrated, the circuit to the controlling relay *g* will be closed and the circuit to the relay *h* will be opened, and therefore the platen will not operate by reason of the engagement of the nose on the armature 40 with the nose 43 on the dog 44.

When the device is to be arranged for individual operation one or more of the switches *e* is closed depending upon the selection desired, and the switch blade 37 is engaged with the contact 36 and a circuit as follows is set up: Current flows from the source *i* through the conductor 28, switch blade 37, contact 36, conductor *s* to the various contacts *o*¹ to *o*⁵. A circuit will not be established however until the detecting fingers engage tabs which cause the movable contacts *k*¹ to *k*⁵ to move, and when a contact, or contacts *k*¹ to *k*⁵ is moved into engagement with a contact or contacts *o*¹ to *o*⁵ which are connected through conductors *t*¹ to *t*⁵ to contacts *x*¹ to *x*⁵ they are connected with contacts *y*¹ to *y*⁵ of the closed switches. Therefore, current will flow from the engaged of the contacts *y*¹ to *y*⁵ through the conductor 26 to one terminal of the winding of the relay *g* and through the conductor 27 back to the other terminal of the source *i*. It is manifest that during this operation the controlling relay *g* has been de-energized and therefore the spring 31 has been holding the armature *m* in engagement with the contact *p* and a circuit to the relay *h* has been opened,

but when the relay *g* is energized, as just set forth, a circuit is closed to the operating relay *h* in the following manner: from the source *i* through the conductor 29, relay *h*, conductor 30, armature *m*, contact *n*, for the armature *m* will have been attracted by the relay *g* and will be engaging this contact, and from this point the circuit is established through conductor 35 to contact 36, switch blade 37 and conductor 28 to the other terminal of the source *i*, and it is therefore apparent that the operation of the dog 46 and roller 47 will be performed in a manner previously described to control the operation of the platen *p*, for the action of the armature 40 in this instance will be the same as that previously described.

The selector mechanism is arranged in inoperative position by disposing the switch blade 37 in the intermediate position illustrated. When the controlling relay *g* is de-energized the spring 31 holds the armature *m* in engagement with the contact *p*. Thus when the switch blade 37 is first moved into engagement with the contact 33 it might be possible that the operating relay *h* would be energized prior to the time the relay *g* is energized to attract the armature *m* and disengage it from the contact *p*, for it is apparent that the contact *p* in the conductor 32, 90 against which the armature *m* will have been resting prior to energizing of the relay *g*, is connected to the contact 33 and current therefore would be supplied to the relay *h*. This would cause a fluttering of the operating relay *h* which might result in operation thereof. This is prevented however by providing much more resistance in the operating relay *h* than in the controlling relay *g*, and due to the high resistance in the relay *h* current will not flow therethrough prior to the time the relay *g* is energized and in this manner fluttering of the relay *h* is prevented. Moreover any back flow or leakage in the circuit will not be detrimental to the proper operation of the 100 device by reason of the difference in resistance between the relays *g* and *h*.

It is apparent from the foregoing description that I have provided a selector mechanism which may be easily arranged to either bring about a group selection or individual selection as may be desired, and that this may be readily controlled by a switching-over device that may be shifted into different positions that may be used to bring about different 115 types of operation.

What I claim and desire to secure by Letters Patent is:—

1. In a printing machine which has means for sequentially moving printing devices 125 therethrough, a platen, means for operating said platen, and means for connecting the platen to the operating means, the combination of an operating relay for controlling the connecting means, a controlling relay, an 130

- armature movable by said controlling relay, a contact engageable by said armature when said controlling relay is energized, a contact engageable by said armature when said controlling relay is de-energized, means for selectively connecting either of said contacts in circuit with the operating relay, a plurality of circuits each in series with the controlling relay, controlling means for said circuits operable by means on the printing devices, means for selectively regulating said circuits to control said controlling relay whereby to permit movement of the armature controlled thereby into engagement with the contact connected in circuit with said operating relay by said selective connecting means.
2. In a printing machine which has means for sequentially moving printing devices therethrough, a platen, means for operating said platen, and means for connecting the platen to the operating means, the combination of a relay for controlling the connecting means, a second relay for controlling the first relay, a plurality of sets of contacts, a plurality of movable contacts respectively disposed between the contacts of each set and normally engaged with corresponding contacts of the sets, means operable by means on the printing devices for moving said movable contacts from engagement with the contacts normally engaged thereby into engagement with the other contacts of the sets, a selecting switch, conductors connected to corresponding of the contacts of each set and to terminals on said selecting switch, conductors separately connected to the contacts on said selecting switch, and means operable by said second relay for connecting either of the conductors to said first relay, said selecting switch determining which of said conductors and which of said sets of contacts shall control operation of the device.
